UNITED STATES PATENT OFFICE

EDWARD ROSCOE BLACK, OF CHICAGO, ILLINOIS, ASSIGNOR TO BLACK SYSTEMS INC.,
OF CHICAGO, ILLINOIS, A CORPORATION OF ILLINOIS

ROOFING SHINGLE

Application filed January 13, 1927. Serial No. 160,803.

My invention relates to roofing shingles and a method of producing them. It is particularly applicable to shingles made from flexible prepared roofing materials.

One of the objects of my invention is to provide an improved shingle made from the ordinary variety of flexible prepared roofing material.

Another object is to provide a shingle which may be readily cut without waste from standard width strips of flexible prepared roofing material.

Another object is to provide an improved shingle of the locking type.

Another object is to provide a shingle of the locking type in which the tendency to crack and tear at the locking or overlapping edges is reduced.

Another object is to provide a locking shingle without slots or slits.

Another object is to provide a shingle which may be economically applied.

Another object is to provide a locking shingle wherein the locking elements also serve as guides and gages for the proper laying of the same.

Another object is to provide a shingle which, when applied to a roof, provides adequate protection with relatively little unnecessary overlap.

Another object is to provide shingles which, when laid on a roof, tend to deflect the water toward the center of and away from the edges of each longitudinal or up and down row.

Another object is to provide an improved type of shingle which lends itself to the production of a wide variety of designs when laid on a roof.

Another object is to provide shingles which may be laid upon a roof with relatively uniform distribution of material over the roof.

Another object is to provide an improved method for producing shingles of the locking type.

Other objects and advantages will herein-after appear.

An embodiment of the invention is illustrated in the accompanying drawings where-

Fig. 1 is a plan view of one form of shingle embodying the features of my invention,

Fig. 2 illustrates the manner in which such shingles can be cut from a narrow strip of roofing material without waste,

Fig. 3 represents the excision of such shingles from standard double width roofing strips, and

Fig. 4 shows the manner in which such shingles are applied.

A roofing shingle made in accordance with my invention has parallel straight top and bottom edges with irregularly incised lateral or side edges. The incisions on the two sides are similar, but opposed so that by inverting one shingle and fitting its side edge against the side edge of another shingle which is not inverted, the two side edges will contact at all points.

In the production of these shingles therefore they can be excised from a standard width strip of prepared roofing material, alternate shingles being inverted, without any waste whatever in the material of the strip.

An individual shingle includes a head portion and a shank portion each provided with laterally projecting tabs, the tabs on the shank resulting in a recess in said shank. These shank recesses correspond in contour and dimensions with the tabs or projections on the head. The sides or edges of the head tabs and shank are parallel to each other.

When the shingles are laid in position on the roof the tabs on the shank of the shingles in each row or course underly and interlock with locking corners of contiguously placed shingles of the preceding row or course. Accordingly, in order that the shingles may be laid so that those in the same row do not overlap but merely abut each other, the distance from the locking edge of a shingle to the center thereof should be substantially the same as the distance from the inner margin of the recess in the shank to the line of the extreme outside edge of the tab on the head. These dimensions being the same, the tabs or projections on the heads of shingles laid side by side will just abut but will not overlap. These features will be more apparent

from a consideration of the detailed description.

Referring first to Figs. 1 to 4, the shingle is provided with top and bottom edges 10 and 11 respectively, these edges being straight and parallel to each other. When cut from a standard narrow strip of roofing material, as shown in Fig. 2, they constitute the outside edge of the strip. The side edges designated 10 generally 12 and 13 are irregularly incised in the sense that the projections on any side are not of regular occurrence. They are regular, however, in the sense that they are of definite configuration and with respect to 15 each other are regular, being similar in design but opposed in direction. This permits the shingles to be cut without waste, by inverting alternate shingles in the manner indicated in Figs. 2 and 3.

20 Each shingle is provided with a parallel sided shank 14 and a main body portion 15. The body portion may again be considered as constituting a head portion 15a and a connecting body portion 15b. The pertinence of 25 this division of the shingle and the function of the different portions thereof will become more apparent when reference is made to the application of the shingles to a roof.

The shank portion 14 is provided with tabs 30 17 and 18 while the head portion is provided with tabs or extensions 21 and 22, the outer side parallel edges of these tabs 21a and 22a constituting the outermost edge of the shingle. On the connecting portion 15b of 35 the main body portion angular projections 23 and 24 occur. When the shingles are laid upon a roof the tabs 17 and 18 of each shingle in the row or course being applied are adapted to abut the bottom edges of contiguous projections 40 23 and 24 of two adjacent shingles of the preceding row. When the shingle is being applied the inner edges 12a and 13a of the shank act as guiding edges for the shank and abut edges 12b and 13b of the 45 two interlocking shingles of the next preceding row, the edges 12b and 13b therefore constituting guiding edges for the main body portion of the shingle. When the shingle is drawn upwardly into place the corners 23a 50 and 24a constituting shingle locking corners, are in firm contacting relationship with corners 17a and 18a between the tabs on the shank and the portion of the shank of restricted width. Thus the interlocking edges 55 12a and 13a of the shank meet tabs 17 and 18.

60 In order further to explain the features of my shingle, a center line representing the longitudinal axis of the shingle is shown in a vertical dotted line in Fig. 1, running through the center of the shingle. At the 65 left of the figure is a dotted line parallel to

the longitudinal axis line and extending from edge 21a representing the outermost edge of the shingle, that is, where the shingle is widest. Now, in order that shingles in the same row may be laid so as just to abut and not overlap (that is so that edges 21a and 22a of two shingles placed side by side just meet or abut each other, but do not overlap). The distance "X" from the locking corner 23a to the longitudinal axis or center line of the shingle should be the same as the distance "Y" from the locking corner 17a to the outermost marginal line of the shingle. Stated in another way the distance from the guiding edge on the main body portion of the shingle to the longitudinal axis thereof is the same as the distance from the guiding edge on the shank to the outermost edge of the shingle.

The tabs formed on the shank result in a recessed portion of such shank, the distance 35 across the shank in the region of the recess being the narrowest width of the shingle. The inner edges of the recess in the shingle shown in Fig. 1 constitute the guiding edges 12a and 13a and in order for the shingle to 40 be cut without waste it is necessary that these edges have the same length as the edges 21a and 22a respectively on the head. The intermediate portions of the lateral incised edges 45 may be made to vary in any way desirable and the shingle still cut without waste, because these intermediate edges are complementary to each other. By keeping these main points in mind, shingles may be made having a great variety of shapes and resulting in different designs when laid upon a 50 roof.

Fig. 4 shows the application of shingles of the type shown in Fig. 1 to a roof, and illustrates, in a general manner, the appearance 105 of the completed roof. The shingles are laid from the bottom or eave edge of the roof to the top or ridge thereof. After the first row or course of shingles has been placed along the eave edge of the roof with the extension 110 edges 21a and 22a abutting and the bottoms 11 lowermost, then the shingles of the next higher row are caused to partially overlap the first row with the tabs 17 and 18 of the shingles of the overlapping row extending 115 under projections 25 and 26 of the shingles of the first row and interlocking therewith at locking corners 23a and 24a. The resulting second or overlapping row of shingles will then have their edges 21a and 22a closely 120 abutting without overlapping and will be in position to in turn become the underlying and locking row for the shingles constituting the next or third row. This procedure is repeated until the roof is covered. As a shingle 125 is applied, it is fastened in place by a suitable fastener, such as a nail, through a portion of the shingle, which when the roof is completed will not be exposed to view. When the roof is completed with shingles of the form shown 130

in Fig. 1, the design of the roof is a succession of staggered T's. The portion exposed in this design constitutes the shank portion of the shingle less the tabs and a portion of the main body of the shingle bounded by guide edges 12b and 13b, excluding the projections 23 and 24 and extending longitudinally above the locking corners 23a and 24a.

With the shingles formed and laid as just described, the edges 21a and 22a of adjacent shingles in the same row abut each other without overlapping below the central portion of the head of the next higher row while along their edges the overlapping may result in several additional thicknesses. Thus the shingles may sag somewhat along the centers and form in effect shallow longitudinal channels or gutters 30 (Fig. 4) down which the water may flow when escaping from the sloping roof and thereby tending to keep the water away from the longitudinal overlapping edges. This lessens the tendency of the water to seep through the longitudinal or up and down joints between the overlapping shingles. The channel is so shallow that it is not immediately discernible and therefore in no way detracts from the pleasing design of the completed roof. It is, however, sufficiently deep for the accomplishment of its purpose.

Having thus illustrated and described the nature and an embodiment of my invention, what I claim and desire to secure by United States Letters Patent is as follows:

1. A shingle having a head with a straight upper edge, a parallel sided shank which is relatively narrow in comparison to the width of the head and has a straight lower edge, a body portion interconnecting the head and shank and of a width intermediate the head and shank, and laterally projecting parallel sided tabs on the head and the outward end of the shank, the vertical length of the head tabs being the same as the vertical length of the shank exclusive of the vertical length of its tabs.

2. A shingle having a substantially rectangular head with a tab projecting centrally from each side thereof, a substantially rectangular shank relatively narrow in comparison to the width of the head, a body portion interconnecting the head and shank and of a width intermediate the head and shank, said intermediate portion having locking corners in opposite sides, and a tab projecting laterally from each side of the outer end of the shank to engage the interlocking corners of shingles of a preceding course, the length of the head tabs being equal to the length of the shank exclusive of the length of its tabs and being less than the distance between the locking corners and the lower limits of the head portion.

3. A roofing shingle of flexible weather-proof material comprising a head having a straight upper edge and a tab at each lateral

side, the side edges of the two tabs being parallel, a parallel sided shank relatively narrow in comparison to the width of the head and having a straight lower edge, a body portion intermediate the head and shank and interconnecting the same, said body portion having a locking corner on each side of the shingle, a tab projecting laterally from each side of the shank at the outer end thereof to engage the locking corners of underlying shingles, the distance from the locking corner to the longitudinal axis of the shingle being substantially the same as the distance from the inner edge of the shank to a line coinciding with the outer edge of a head tab and the vertical length of the head tabs being equal to the vertical lengths of the shank exclusive of the vertical length of the shank tabs.

4. An interlock type shingle formed from a sheet of flexible weatherproof material and comprising a head having a straight upper edge and a tab at each lateral side, the lateral edges of the two tabs being parallel, a substantially parallel sided shank having a straight lower edge, an intermediate interconnecting body portion between the head and shank, said body portion having a locking corner on each side of the shingle and the distance from one such locking corner to the longitudinal axis of the shingle being substantially equal to the distance from a side of the shank to the line of the outer edge of the head tab on the same side of the shingle, and a tab projecting laterally from the end of each side of the shank to engage a locking corner of an underlying shingle, the vertical length of the shank exclusive of its tabs being equal to the vertical length of the head tabs.

In witness whereof, I hereunto subscribe my name this 11th day of January, 1927.

EDWARD ROSCOE BLACK.
